US00D835364S

(12) **United States Design Patent** (10) Patent No.: **US D835,364 S**
(45) Date of Patent: **** Dec. 4, 2018**

(54) **ELECTRONIC DEVICE**

(71) Applicant: **Garmin Switzerland GmbH**,
Schaffhausen (CH)

(72) Inventors: **Juhee Lee**, Olathe, KS (US); **Gary J. Domke**, Shawnee, KS (US); **Aaron J. Lindh**, Shawnee, KS (US); **Todd P. Register**, Olathe, KS (US); **Darren Mitchell Nakonechny**, Tucson, AZ (US)

(73) Assignee: **Garmin Switzerland GmbH** (CH)

(**) Term: **15 Years**

(21) Appl. No.: **29/571,854**

(22) Filed: **Jul. 22, 2016**

(51) LOC (11) Cl. **30-99**

(52) U.S. Cl.

USPC **D30/199; D10/104.1**

(57) **CLAIM**

The ornamental design for an electronic device, as shown and described.

DESCRIPTION

FIG. 1 is a front perspective view of an electronic device according to the present invention;

FIG. 2 is a rear perspective view of the electronic device;

FIG. 3 is a top view of the electronic device;

FIG. 4 is a front view of the electronic device;

FIG. 5 is a bottom view of the electronic device;

FIG. 6 is a rear view of the electronic device;

FIG. 7 is a right side view of the electronic device; and,

FIG. 8 is a left side view of the electronic device.

The structural features depicted by broken lines have been shown for the purpose of illustrating portions of the electronic that form no part of the claimed design.

1 Claim, 3 Drawing Sheets
